CRATE FOR SHEET MATERIALS

Charles R. Birdsey, Hinsdale, Ill., assignor to
United States Gypsum Company, Chicago, Ill.,
a Corporation of Illinois

Application June 22, 1929. Serial No. 372,825

9 Claims. (Cl. 206—60)

This invention relates to a crate for use in shipping sheet materials, and has reference more particularly to a crate for gypsum wallboards suitable for use where abuse in handling is unavoidable such as in export shipments and domestic water transportation.

Gypsum wallboards require protection to keep the surfaces and corners from being marred or broken in shipment. I have tried out various types of wood crates for shipments of these gypsum wallboards, but in the main they have proved to be unsatisfactory and easily broken so that damage to the boards results, unless very expensively made and an exceptionally heavy crate construction used.

An object of this invention, therefore, is to provide a shipping crate which is made of standard structural angles together with other standard parts readily procurable on the open market.

Another object of the invention is to provide a shipping crate for use in export shipments which is collapsible and can be returned to the shipper at low cost.

A further object of the invention is to provide a metal shipping crate which will protect the edges of gypsum wallboard from damage; also to improve shipping crates in other respects hereinafter specified and claimed.

Reference is to be had to the accompanying drawing forming a part of this specification, in which

Figure 1 is a perspective view of my improved shipping crate,

Figure 2 is a fragmentary, end elevation of one corner of the shipping crate,

Figure 3 is a fragmentary, sectional elevation through the crate on the line 3—3 in Figure 1, and

Figure 4 is a fragmentary, sectional, plan view taken through the crate on line 4—4 of Figure 2.

My improved shipping crate is especially useful in shipping sheet materials of any kind but especially sheets subject to easy damage in transportation, such as gypsum wallboards or plasterboards, as well as pulp wallboards, veneers, metal sheets, etc., which are generally stacked in face to face relationship in sizeable piles for purposes of transportation. Reference numeral 10 indicates the sheet material to be shipped. A plurality of preferably four angle strips 11 extend along the longitudinal corners of the stack of sheet material 10 and a plurality of preferably four angle strips 12 extend along the transverse corners of the stack, so that all of these eight corners of the stack are metal protected during shipment. It will be noted from inspection of Fig. 1, which illustrates a preferred embodiment, that the legs of the angle strips 11 all preferably extend inwardly, while with the angle strips 12, one leg

or flange 13 of each angle extends inwardly to lie in abutting position along the stack of boards or the like, and the other leg 14 of said angle extends outwardly from the stack. Suitable slots 15 are preferably formed in the angle legs 13 so that sufficient clearance space is provided for engagement with adjacent legs of the angle strips 11. The angles on each face of the stack are thus grouped together to form a pair of rectangular frames.

Separable angle strips 16 are provided along the perpendicular or stack corners of the pile of sheets, said angle strips being somewhat shorter than the vertical dimension of the pile of sheets when said sheets are loosely piled or in unclamped position, so that space 17 is left between the top of said angle strips 16 and the adjacent leg of angle strip 11. Vertical bolts 18 pass through superjacent square holes in the angle legs 14 and the angle strip 11 adjacent each of the separable

angle strips 16, these bolts being preferably two in number at each corner of the stack. These bolts are directed inwardly from each face of the crate and the inner ends are adjustably secured together by means of a turnbuckle 19, so that the

boards may be securely clamped together and so that the space 17 will be reduced to zero with the top of angle strips 16 resting securely upon the lower faces of the upper legs of angle strips 11. Thus the separable angle strips 16 form columns when the crate is clamped together securely, and prevent the crushing of such sheet material as gypsum board or the like when several of the crates are piled one upon the other. The heads

20 of the bolts are preferably rounded so that the loaded crate may be moved freely along the floor or other smooth surface without interference by the bolts. Where the bolts pass through the angle legs a square section 21 is provided on the bolts to prevent turning of the bolts as the

turnbuckles 19 are adjusted.

It should be noted that by clamping the sheets together, they act as a composite unit, instead of individually, as a means to resist deflection from rough handling, and in combination with the

crate members make the whole unit stiff and rigid. All corners of the sheets are protected from damage during shipment. In actual practice I have found that as much as 4400 pounds of material such as gypsum wallboard may be shipped in a single crate because of the great strength thereof.

The crate is easily collapsible after it has reached its destination and packs into a small space so that it can be returned to the shipper at a very low cost, for shipment and handling charges.

Standard structural steel shapes are preferably used throughout for the construction of the crate, making its cost of construction very low, but it is understood of course that special shapes may be used. While the parts of the crates
